UNITED STATES PATENT OFFICE.

HENRY SELIGMAN AND EMMA SELIGMAN, OF IRVINGTON-ON-HUDSON, NEW YORK; SAID HENRY SELIGMAN ASSIGNOR TO SAID EMMA SELIGMAN.

MECHANICAL TELEPHONE.

SPECIFICATION forming part of Letters Patent No. 320,181, dated June 16, 1885.

Application filed March 19, 1884. (No model.)

To all whom it may concern:

Be it known that we, HENRY SELIGMAN and EMMA SELIGMAN, residing at Irvington-on-Hudson, New York, have invented certain new and useful Improvements in Mechanical Telephones, of which the following is a specification.

Our invention relates, primarily, to a telephone which is especially adapted to be used and operated in large factories, printing-establishments, warehouses, stores, and, in fact, any and all places where there is more or less noise and confusion during business hours, and a consequent difficulty in conveying audible sounds beyond a very short distance. As at times it is extremely difficult to detect the import of a message when the receiving-diaphragm of the telephone is exposed where there is any great amount of external disturbance, and the sounds which are transmitted over the wire are blended with these external sounds, whereby their force and individuality are greatly diminished, it becomes important to provide a simple and effective means for overcoming this difficulty.

The objects, therefore, of our present invention, are to greatly increase the volume of sound transmitted and received, at the same time preserving intact its distinctness, and also by means hereinafter described, of transmitting the sounds received from a distance directly to both ears, thereby preventing any confusion of sounds and rendering all messages distinctly audible.

To this end our invention consists of an acoustic telephone similar to that shown and described in our Letters Patent issued April 1, 1884, and is provided with a box or casing, preferably circular in shape, and made of wood or any other suitable material. This box or casing is provided with two main diaphragms having filamentary connections between them. The diaphragms are each provided with a ring upon their exterior sur-

face. To these rings the connecting-filaments are attached. Upon the outside of the outer diaphragm are also placed cords or strings extending from the outer edge of the diaphragm to the ring, to which they are attached. The filaments which connect the

diaphragms are also attached to these cords at suitable places. We have found by experiment that these cords intensify and increase the volume of sound very much by causing a unity of action between the two diaphragms. A re-enforce of silk or other textile fabric is arranged directly beneath the outside diaphragm. The inner diaphragm is constructed of the same material as the outer—namely, oiled parchment or sheepskin—and the two are connected, as above stated, by filaments. Fastened upon the outside of this inner diaphragm is a re-enforcing-plate, preferably formed of cork, and upon this plate rests the ring around which the filaments are strung. The ring is provided with a cap, as shown, and to this cap is attached the line-wire. Against the inside of this cap is secured a tube or bar which extends from said cap through the inner and outer diaphragms to a suitable distance—say, half an inch, more or less—beyond the latter. This tube is provided on its outer end with an auxiliary diaphragm of metal, pasteboard, or other suitable material. This tube may have cork or wood inside of it, or it may remain hollow, as experience dictates is the best. The auxiliary diaphragm may be connected to the tube by means of a small screw or pin extending into the wood or cork of the tube; or the diaphragm may be provided with a stud on its inner face, which is adapted to screw into the tube. The sound vibrations received on this diaphragm are conveyed directly to the line-wire through the medium of the tube and the cap before mentioned. Having thus three diaphragms elastically connected and vibrating in perfect unison, the transmitting power of the instrument is greatly increased. This auxiliary diaphragm, while being elastically connected with the others, performs its functions entirely independently of the main diaphragm, and has been found by experiment to give very satisfactory results.

For the better conveyance of sound under certain circumstances we place upon the exterior of the instrument a trumpet or reverberating-chamber formed, preferably, of metal, and hemispherical in shape. To this we connect one or more speaking or hearing tubes.

Other details of our invention will be hereinafter specifically referred to.

Referring to the accompanying drawings, which form part of this specification, Figure 5 1 represents a sectional view embodying most of our present improvements. Fig. 2 is a plan view of the exterior face of the inner diaphragm. Fig. 3 is a similar view of the outer diaphragm. Fig. 4 represents an elevation of the trumpet 10 or reverberating chamber and the double speaking and hearing tube. Fig. 5 represents a sectional view of what we term our "auxiliary diaphragm," showing its connections through the diaphragm with the line-wire direct. Fig. 15 6 is a plan view of the same.

In the drawings, A represents the box or casing of the telephone, which may be constructed of three parts, *a a' a''*. In the cross-section, Fig. 1, the annular portion *a''* is represented somewhat thicker than the other parts. This form we have found gives better results than where it is hollowed out, as the latter reproduces and confuses the sounds within the instrument.

25 B B' are the outer and inner diaphragm, respectively. They are made, preferably, as before stated, of parchment or sheepskin. They may be oiled or varnished, or both. For a suitable varnish we have employed collodion 30 with satisfactory results. This serves to stiffen the diaphragm and render it impregnable to moisture. A re-enforce of silk (shown at *b*) is placed directly under the outer diaphragm.

C are cords, arranged upon the exterior of 35 the outer diaphragm, extending from the circumference inward to the ring D, to which they are attached, and which they serve to support. The object of these cords is to assist in carrying the vibrations to the center of the 40 diaphragm. Filamentary connections *c'* extend from points *c* of the cords C and *d* of the ring D to the ring E on the inner diaphragm. Between the latter and the ring E we place a re-enforcing plate, F, preferably formed of 45 cork, which is attached to said diaphragm and vibrates in unison with it. This plate is not only beneficial as a re-enforce, but also serves to prevent the abrasion of the face of the diaphragm by the vibration of the ring thereon. 50 Upon the ring E is mounted a cap, G, and to this cap, at its central portion, the line-wire H is attached.

The portion *a* of the telephone case or box is provided with a plate, I, having a hollow 55 stud, *i*, through which the line-wire extends, the said hollow stud being provided with a screw-thread on its outer face. By this means the telephone may readily be attached to the wall and centered. Against the inner surface 60 of the cap G is secured a tube or bar, J, which passes loosely through both the inner and outer diaphragms without interfering with their functions, and is provided at its outer end with an auxiliary diaphragm, K, of any suitable 65 size, and formed of metal, pasteboard, or other suitable material. If a tube is employed, it may either be left hollow or filled with cork or

wood. In this case the diaphragm can be attached by means of a pin. It may also, however, be provided with a stud having a screw-thread on its inner surface, which is adapted to fit around the aforesaid tube J.

Attached to the instrument and facing the outer diaphragm, B, is a trumpet or reverberating-chamber, L, formed, preferably, of 75 metal, the said trumpet being provided with extensions *l l'*. The trumpet L is provided with an annular flange, M, which fits under and is confined by a ring, N, attached to the telephone-casing. This arrangement provides 80 means for turning the trumpet without changing the position of the telephone itself.

R R are continuations of the tubes, and may be formed of rubber or any other flexible material. They are adapted to fit over the ends 85 of the tubes *l l'*. By subdividing the tube means is afforded for applying the instrument to both ears at the same time. Suitable calls consisting of reeds or whistles S are also provided. They may be inserted in the ends of 90 the tube or in the casing of the telephone itself. Both forms are illustrated in Fig. 1.

Having thus described our invention, what we claim as new therein, and desire to secure by Letters Patent, is—

95

1. In a telephone, the combination, with a main diaphragm and a chamber, of a supplementary diaphragm and a central stem for suspending said supplementary diaphragm within said chamber and connecting it with said main diaphragm, substantially as and for the purpose set forth.

2. In a mechanical telephone, the combination, with a line-wire and a main diaphragm, of a supplementary diaphragm connected to 105 said main diaphragm by a central stem, substantially in the manner and for the purpose set forth.

3. In a mechanical telephone, the combination of an inner and an outer diaphragm, the former being provided with a re-enforce of cork, a metallic ring, and a cap, and the latter with a metallic ring and radiating vibratory cords, the said rings and cords having filamentary connections between them and connection with the line-wire, as described. 115

4. In a mechanical telephone, the combination of the line-wire, a main diaphragm having a central aperture, a metallic cap attached thereto, a tube or bar secured to said cap and extending through said opening, and an auxiliary diaphragm secured to the end of said tube or bar, as and for the purpose set forth. 120

5. In a mechanical telephone, the combination, with a line-wire and a main diaphragm, 125 of an auxiliary diaphragm, the said auxiliary diaphragm having means of connection with the line-wire, consisting of a tube or bar extending through the main diaphragms, but adapted to vibrate independently of them, 130 substantially as set forth.

6. In a mechanical telephone, the combination, with a pair of diaphragms, a ring on the outer face of each, and filamentary connections

between said rings, of a re-enforce, substantially as described, interposed between the ring and the face of one of the diaphragms and the line-wire, all arranged and adapted to 5 operate in the manner and for the purpose set forth.

7. In combination with the box or casing of a mechanical telephone provided with an annular flange, with the trumpet also provided 10 with a flange whereby the said tube and the trumpet may be turned and adjusted, as and for the purposes described.

8. In a mechanical telephone, the combination, with a line-wire, a diaphragm, and a ring placed against said diaphragm, substantially 15 in the manner and for the purpose described, of a re-enforce interposed between said diaphragm and ring for preventing the abrasion of the former by the latter, as explained.
